J. J. SMITH

PELTS OR HIDE STRETCHER

Filed Nov. 3, 1925

INVENTOR=

John J. Smith,
By *Meader, Palmer, Copeland & Tice*,
ATTORNEYS-

UNITED STATES PATENT OFFICE.

JOHN J. SMITH, OF ALLSTON, MASSACHUSETTS.

PELT OR HIDE STRETCHER.

Application filed November 3, 1925. Serial No. 66,499.

This invention relates to hide or pelt stretchers particularly of that type adapted to be used for the purpose of stretching and drying raw fur-bearing skins, an object of 5 the invention being to provide an improved stretcher embodying a spring frame which is adjustable to adapt itself to hides or pelts of different sizes, wherein the device is provided with improved means for holding the 10 spring frame within the hide or pelt in stretched condition, such means being in the form of an improved spreader bar connecting the spring arms of the frame together and adapted to be readily and easily manipulated, relatively simple and cheap in construction, incapable of causing injury to the fur or pelt, and compact in construction so as to permit the frames carrying the pelts to be stacked conveniently while at the same 15 time occupying a minimum of space.

A further object of this invention is to provide an improved fur or pelt stretcher of the type comprising a spring frame having expansible and contractible spring arms 20 adapted to maintain the pelt or hide in the proper stretched condition, and in which improved means is provided not only for locking the spring arms of the frame in adjusted position but also for clamping the tail piece 25 of the fur or hide in stretched condition.

Other objects of this invention will appear in the following description and appended claims, reference being had to the accompanying drawings forming a part of this 30 specification wherein like reference characters indicate corresponding parts in the several views and wherein:

Fig. 1 is a plan view illustrating a stretching apparatus constructed in accordance 35 with my invention.

Fig. 2 is a similar view illustrating the pelt or fur in position upon the frame, and

Fig. 3 is a sectional view taken substantially on the line 3—3, Fig. 1 in the direction of the arrows, and particularly illustrating the improved spreader bar.

Before explaining in detail the present improvement and mode of operation thereof, I desire to have it understood that the invention is not limited to the details of construction and arrangement of parts which are illustrated in the accompanying drawings, since the invention is capable of other embodiments, and that the phraseology which 55 I employ is for the purpose of description and not of limitation.

Referring to the drawings wherein I have illustrated a present preferred embodiment of my invention, it will be seen that the stretcher comprises a spring frame which is 60 preferably formed from a relatively heavy wire bent intermediate its ends at 9 to provide rearwardly extending spring arms 10 and 11. The spring arm 10 is somewhat longer than the opposite arm 11, and at its rear end is bent substantially at right angles and inwardly to form a connecting arm 12, the free end of which passes through an eye or loop 13 formed at the rear end of the spring arm 11. The transverse connecting 65 arm 12 at its end is bent to provide a handle 14, which also performs the function of interlocking the spring arms together and preventing the portion 12 from becoming disconnected from the eye or loop 13. 70

From the foregoing construction, it will be seen that the spring arms 10 and 11 may be contracted and expanded under tension, and in order to connect the arms together in adjusted positions with respect to each other, a spreader bar 15 is provided. This bar may be formed from a flat metal plate which at one end is stamped out or otherwise formed to provide a longitudinal guide slot 16 adapted to slidingly receive the wire-formed spring arm 10. The plate 15 is also stamped or otherwise formed at its opposite end to provide a similar longitudinal guide slot 17. The slot 16 at its upper longitudinal edge is formed with a plurality of spaced 80 projections or teeth 18 forming therebetween recesses or notches 20 of sufficient size to receive and hold the arm 10 therein. In like manner the longitudinal guide slot 17 at its upper edge is provided with a corresponding series of projections or teeth 19 forming therebetween recesses or notches 21 for receiving the spring arm 11. 85

Secured to the upper edge of the spreader bar 15 by means of a clamping plate 23 is a leaf spring 22, which spring extends lengthwise of the spreader bar and at its free end is bent or flared upwardly at 22'. This spring is preferably of considerable strength so that when flexed to permit the insertion of the tail piece of the fur between the spring and the spreader bar, the fur tail piece will be firmly clamped in position. 90

As shown in Fig. 2, a fur pelt or hide 26 is mounted in position upon the spring frame. In using the stretching apparatus the pelt is turned inside out and the nose 105

9 of the spring frame is inserted into the pelt and the latter drawn over the frame, as shown in Fig. 2. By grasping the spring arms and expanding them, the pelt may be stretched to the desired extent. It will be seen that when the arms 10 and 11 are thus spread or expanded outwardly, the rear ends of the arms will slide freely in the guide slots 16 and 17 along the lower straight edges thereof. When it is desired to clamp the arms in adjusted relative positions under tension, it is merely necessary to force the spreader bar 15 downwardly, or in a vertical direction, thereby causing the arm 10 to enter one of the recesses or notches 20 and causing the arm 11 to enter one of the recesses or notches 21. The tension exerted by the spring arms will hold them firmly in position within the notches by frictional engagement against the edges of the adjacent teeth or projections 18 and 19. The tail piece 27 of the fur may thereupon be inserted beneath the spring 22 by grasping the bent end 24 of the spring and flexing it sufficiently to permit the insertion of the tail piece between the spring and the spreader bar. Thereupon the tail piece may be stretched to the desired extent and when the spring 22 is released, it will firmly clamp the tail piece in position.

In the preferred form the spring arms 10 and 11 at the inner edges thereof are provided with spaced projections or teeth 24 and 25 respectively. These teeth cooperate with the teeth of the guide slots 16 and 17 so as to hold the spreader bar in position against sliding movement upon the frame.

From the foregoing operation and considering the present construction, it should be noted that the spring frame may be easily expanded or contracted under tension against the fur pelt and locked in such expanded or contracted position by means of the spreader bar 15, it being merely necessary to shift the latter in a direction transverse to the movement of the spring arms longitudinally of the spreader bar so as to cause the arms to enter the notches or recesses 20 and 21. In addition it should be noted that the spreader bar 15 projects but a slight distance at opposite faces of the spring frame and when the pelt 26 is mounted on the frame, the entire frame carrying the pelt, together with the spreader bar, is substantially flat from end to end at opposite faces thereof, and as a result a large number of frames carrying pelts may be stacked one upon the other compactly so as to occupy a minimum of space.

It is to be understood that by describing in detail herein any particular form, structure, or arrangement, it is not intended to limit the invention beyond the terms of the several claims or the requirements of the prior art.

What I claim is:

1. A hide stretcher comprising a frame having spaced expandible and contractible spring arms, a spreader bar slidable on said arms and connecting the arms together, said bar having means for permitting relative movement of said arms longitudinally of the bar and also having means for permitting movement thereof relatively to the arms in a transverse direction to lock the arms in various adjusted positions.

2. A stretcher comprising a spring frame having expandible and contractible spring arms, a spreader bar connecting said arms together and slidable thereon, said bar having a longitudinal guide slot for receiving each arm formed at one longitudinal side with a plurality of recesses for adjustably locking the arms in position.

3. A stretcher comprising a spring frame having expandible and contractible spring arms, a spreader bar connecting said arms together and slidable thereon, said bar having a longitudinal guide slot for slidably receiving each arm, said slot having formed at one longitudinal edge a plurality of teeth spaced apart to lock said arms therebetween in adjusted position.

4. A stretcher comprising a spring frame having expandible and contractible spring arms, a spreader bar connecting said arms together and slidable thereon, said bar having a longitudinal guide slot for receiving each arm formed at one longitudinal side with a plurality of recesses for adjustably locking the arms in position, and spring means connected with said bar for clamping a tail piece of the fur in position.

5. A stretcher comprising a spring frame having relatively expandible and contractible arms, a spreader bar connecting said arms together and slidable thereon, said bar having a longitudinal guide slot for slidably receiving one of said arms, said slot having formed at one longitudinal edge thereof a series of notches for adjustably locking said arm under tension with relation to the other arm, and a leaf spring secured at one end only to said bar for clamping a tail piece of the fur in position.

6. A hide or pelt stretcher comprising a frame having relatively expandible and contractible arms, a spreader bar connecting said arms together and slidable thereon, and a spring secured to said bar for clamping a tail piece of the pelt in position between the spring and the bar.

7. A hide or pelt stretcher comprising a spring frame having expandible and contractible spring arms, a spreader bar connecting said arms together and slidable thereon, and a flat spring secured at one end only to said bar for clamping a tail piece of the pelt in position between the spring and the bar.

8. A pelt stretcher comprising a frame having spring arms and a spreader bar for connecting said arms, said spreader bar having formed therein adjacent each end a series of notches for selectively receiving the adjacent arm, said arms being freely movable into and out of said notches by a relative lateral movement of said arms and bar.

9. A pelt stretcher comprising a frame having spring arms and a spreader bar for connecting said arms and having means for engaging and securing a portion of a pelt on said frame, said spreader bar having formed therein adjacent each end a series of notches for selectively receiving the adjacent arm, said arms being freely movable

into and out of said notches by a relative lateral movement of said arms and bar.

10. A pelt stretcher comprising a frame having spring arms and a spreader bar for connecting said arms, said spreader bar having formed therein adjacent each end a series of notches for selectively receiving the adjacent arm, said arms being freely movable into and out of said notches by a relative lateral movement of said arms and bar, said arms having teeth cooperating with the edges of the notches to fix the position of said bar longitudinally of said arms.

In testimony whereof I affix my signature.

JOHN J. SMITH.
